UNITED STATES PATENT OFFICE

2,489,580

PINCERS

Bertrand Marcoux, Ste.-Marie, Quebec, Canada

Application August 8, 1946, Serial No. 689,258

1 Claim. (Cl. 294—118)

1

The present invention pertains to a novel pair of pincers or tongs designed particularly for holding hot objects, such as dishes and plates, portions of food, cleaning cloths immersed or to be immersed in hot water, and the like.

The principal object of the invention is to provide an extremely inexpensive and simple device of this character, preferably one made of wire. Another object of the invention is to provide such a device that is readily manipulated and opened and closed with one hand.

In the accomplishment of these objects, the device comprises a pair of handle members each of which is formed at one end with a holding jaw. Each such unit consists of a length of wire bent upon itself to form a pair of strands, and the outer ends of the strands are bent divergently to form a pair of arms. The arms are preferably braced and joined by suitable cross members to form a jaw. The handles are pivotally attached to one another adjacent to their respective jaws, so that the jaws become complementary to one another as a holding device.

A novel structure is employed in pivotally holding the handles or units together. One of the pairs of strands is coiled adjacent to the corresponding jaw on an axis perpendicular to the strands. The remaining handle or pair of strands is pivotally held in this coil preferably by being crossed or intersected through the coil. Further, one of the handles is longer than the other and carries a loose ring adapted to be passed over the shorter handle to hold the device in the closed or resting position.

The invention is fully disclosed by way of example in the following description and in the accompanying drawings in which—

Figure 1 is a perspective view of the device;

Figure 2 is a side elevation of the device in open position; and

Figure 3 is a side elevation of the device in closed and holding position.

Reference to these views will now be made by use of like characters which are employed to designate corresponding parts throughout.

In Figure 1 the device is shown to include a wire bent upon itself to form two strands 1 and 2 engaging each other lengthwise for a portion of their length. In the bend of the wire there is preferably formed a coil 3 in order to space the adjacent portions 4 and 5 of the strands to form a handle. Where the strands come into engagement with each other, they are preferably bound by a thin wire coil 6 in order to maintain the desired configuration. A ring 7 loosely 55

2

surrounds contacting parts of the strands for a purpose that will presently be described.

At a substantial distance from the coil 6, the contacting parts of the strands are coiled at 8 and 9, respectively, on a common axis, perpendicular to the strands. From the ends of the coils, the strands are continued respectively as diverging arms 10, having upwardly extending fingers 11. The arms 10 are joined by cross members 12, which are preferably in the form of wire lengths welded to the arms. The arms 10 lie substantially in the plane of the spaced portions 4, 5 of the strands, as may be seen in Figures 2 and 3.

The part of the device thus far described constitutes a handle and one jaw of a pair of pincers or tongs. The remaining jaw and handle is comprised of another length of wire bent upon itself to form strands 14 and 15, engaging each other lengthwise for a portion of their length, directly adjacent to the bend 16 thereof. Beyond the contacting portions 14, 15 the strands are bowed outwardly at 17 and 18 and are then crossed or intersected at 19 through the coils 8, 9. The strands are continued from their intersections as spaced arms 20, similar to the arms 10 and bent at their extremities to form fingers 21, directed towards the fingers 11. The arms 20, like the arms 10, are joined by cross members 22, which are preferably in the form of wire lengths, having their ends welded to the arms 20. The structure 20—22 forms a jaw which is complementary to the jaw 10—12.

As already indicated, the device is designed particularly for holding and carrying small heated objects such as hot dishes, portions of food, cleaning cloths soaked in hot water, and the like. Figure 3 illustrates the use of the device in holding such an object represented by an egg 23. The handle portion 14, 15 has been moved away from the handle portion 4, 5 to spread the jaws and enable the lower jaw to pick up the object. The handle portions are then brought together and retained in this position by slipping the ring 7 over the handle portions 14, 15. The jaws are spread apart to release the object 23 by a reverse operation. The ring 7 is slipped off the handle portion 14, 15, which is then moved away from the strands 1, 2 by a movement of the finger of the hand that holds the handle 4, 5 which for this purpose extends beyond the handle 14, 15. Both handle portions may be enclosed in wood handle bars, if desired.

Although a specific embodiment of the invention has been illustrated and described it will

be understood that various alterations in the details of construction may be made without departing from the scope of the invention as indicated by the appended claim.

What I claim as my invention is:

A pincers comprising a length of wire bent upon itself to form two strands, said strands being bent and spaced apart at their free ends to form a pair of spaced arms, another length of wire bent upon itself to form two strands, the last-named strands being bent and spaced apart at their free ends to form a pair of spaced arms, one of said pairs of strands being coiled adjacent to the corresponding arms and on an axis perpendicular to said strands, the remaining 10 strands intersecting each other in the coiled portion.

BERTRAND MARCOUX.
